TRAFFIC SIGNAL

Filed June 3, 1927

UNITED STATES PATENT OFFICE

LEO M. TORRENCE, OF ARRINGTON, KANSAS, ASSIGNOR TO JO MARGARET TORRENCE,
OF ARRINGTON, KANSAS

TRAFFIC SIGNAL

Application filed June 3, 1927. Serial No. 196,266.

My invention relates to a traffic signal.

The object of my invention is to provide an inexpensive rotary signal.

A further object of my invention is to provide a rotary signal having the indicia on projecting wings confronting the four ways of the street intersections.

A still further object of my invention is to provide a rotary traffic signal having a stationary member with the names of the street on which it is located.

A still further object of my invention is to provide a signal rotatable by mechanical power.

15 A still further object of my invention is to provide a signal device having a single, uncolored lamp.

These and other objects will hereinafter be more fully explained.

20 Referring to the drawings:

Fig. 1 is a plan view of a pedestal mounted signal, parts broken away for convenience of illustration.

Fig. 2 is an elevation of the device, parts 25 broken away for convenience of illustration.

Fig. 3 is an enlarged detailed view of the turning mechanism, partly in section.

Fig. 4 is a sectional plan view of Fig. 3, 30 taken on line IV—IV in Fig. 3.

Fig. 5 is a side view of the rotary arm partly in section.

Fig. 6 is a plan view of Fig. 5, parts removed for convenience of illustration.

35 The mechanism herein disclosed consists of a rotary signal device mounted on a pedestal and is arranged to be centrally positioned at the intersection of streets or other public highways. The signal to be a rotatable type carried by a pedestal 1, the pedestal also functioning as a conduit, the power lines extending therethrough from an underground conduit service (not shown in the drawings).

40 Rotatably mounted on the upper end of the pedestal is a housing 2, having tangentially positioned indicia plates 3, the drawings herein disclosed show four of said plates, the object of which is that the said plates will transversely position to the streets

or highways as controlling means for the traffic on which they confront, the plates extending and facing in opposite directions will read the same signal and be discernible to the traffic traveling in opposite directions 55 on the same street or highway.

It will be understood that the movements of the rotation will be in quadrants successively, the indicia plate always stopping transversely to the street that it controls, the plate extending in opposite direction will also face in opposite direction and will have the word "Stop" thereon, the transversely positioned plate will have the word "Go" on each side thereof, and will likewise face in 60 opposite direction.

65 Note that rearwardly positioned to each of said plates is a housing 2, triangular in shape; in other words the rear walls thereof extend obliquely and connect near the inner 70 end of the transversely positioned plate, the said walls function as a reflector.

75 The indicia plates consist of a glass 4, rigidly positioned in the housing and in close proximity and rearwardly positioned thereto is an opaque plate 5, said plate preferably made of sheet metal and having apertures aligned therein to form letters of the words "Stop" and "Go", the apertures through which the light flows rendering it possible 80 for the traffic to discern the signal and as the present custom is, the plate having the word "Stop" thereon will be red, and the one having the word "Go" thereon will be 85 green.

85 Transversely positioned to the indicia plates are glass panels 6 colored to correspond with the glass in front of said plates, the said panels function as a substitute, and should the glass in said plate become broken 90 the color will still be maintained.

95 Concentrically positioned on the first said housing and upwardly extending therefrom is a housing 7, having glass panels 8 on the four vertical sides thereof, the said glass being colored to correspond with the indicia glass in the same vertical plane therewith.

100 On the under side of the first said housing is a downwardly extending portion 9 having a ball race concentrically positioned as at

A, the said race to register with the race in the upper end of the pedestal, by which means a ball bearing is arranged for the rotation of the housing; downwardly extending from said bearing is a pipe 10, said pipe being rigidly attached to the member 9, rotatable therewith and having means on its extreme lower end by which the housing is rotated; positioned within the member 9 is a reflector 11, as intensifying means for an electric lamp, and its functions as herein-after described.

On a vertical plane with the indicia plates are web members engaging with the corners of the housing, functioning as blinds to obscure from view the illuminated glass panel rearwardly positioned thereto in housing 7.

The socket 14 functions as a bearing for the upwardly extending arms 18, on which is positioned a housing 19, around which the first said housing revolves; the last said housing is preferably made of sheet metal having letters cut therethrough similar to stencil or perforation and aligned to form the letters.

In each of the four sides of said housings will be the names of the streets intersecting for convenience of the traffic, for example, the signal is stationed on the intersection of Main and Tenth, "Main Street" is readable on opposite sides of the housing confronting Tenth Street, and "Tenth Street" discernible on the sides confronting Main Street.

On the lower end of the last said housing is an outwardly extending annular flange 20, to prevent the flow of light between the housing and the glass panels in housing 7, by which means the indicia in the side walls of housing 19 is more clearly defined as the light appears through the apertures forming the letters of the name.

It will be understood that the housing is rigidly maintained in one position, the flange thereof being wide enough to close the diagonal space between the corners of said housing and housing 7 when the side walls thereof are parallel with each other, therefore it is required that a segmental enclosure 21 be placed on the extensions of housings 2, to receive the periphery of the flange, the said flange so engaging will also function as bracing means for housing 2 in its rotation; however, it is not intended that the said flange will contact with the housing 2 at any time. It will be further understood that the lower end of housing 19 is open and the inside walls thereof being bright will function as reflectors, it is readily seen that a single light concentrically positioned, or practically so, and having the reflector elements heretofore described, will be capable of illuminating the interior, thereby rendering all of said indicia readable and also emphasizing the color scheme.

As rotating means for the signal I have

provided a handle 22 rigidly attached to pipe 10 near the lower end thereof, the said handle reciprocatingly engaging in a slot 23, by which means when said handle is rocked to one end of the slot the signal plates are transversely positioned to or caused to confront with the street longitudinally; for example, the indicia will read "Stop" and when rocked to the opposite end of the slot the signal "Go" is brought to view, and by repeating the reciprocations the traffic is controlled. The slot 23 is closed by an arcuated door 23' and when said door is locked the signal cannot rotate; also note that the handle is removable, having a joint as at C, the stud D threadedly engaging in the other portion of the handle.

It will be understood that the signal, as supported by the pedestal, may also be power actuated by applying a mechanical power drive within an annular extension positioned on the shaft of the pedestal.

Such other modifications may be employed as lie within the scope of the appended claims.

I claim:

1. In a traffic signal device, a signal housing of the kind described, a pedestal rotatably supporting the housing, a pipe downwardly extending into the pedestal and rigidly carried thereby, functioning as a conduit, an electric lamp attached to the upper end of the pipe, a housing having arms attached to the upper end of said pipe, said housing axially aligned with said pipe, the numbers or names of the streets cut through the sides of the last said housing, glass panels in first said housing in close proximity to the sides of second said housing and in registry therewith, so that when the first said housing rotates to the parallel alignment of the glass panels to the sides of the second said housing the numbers or names are readable there-through, the second housing remaining in one position at all times, means to operate the space between the stationary housing, a concave reflector concentrically positioned in the rotatable housing as light refraction means for the interior of both of said housings, a downward extending pipe from the rotatable housing to rotatably engage in the shaft of the pedestal, a slot transversely positioned in the pedestal, a handle rigidly attached to the lower end of the last said pipe, the handle to reciprocatingly engage in the said slot as turning means for the rotatable housing to the equivalent of a quadrant to and for, all substantially as shown.

2. In a traffic signal device, a signal of the kind described, a plurality of tangentially positioned indicia plates comprising an opaque member having words cut through and a translucent member to cover the same on the exterior, one pair of the signals to have the word Stop, the other pair transversely to the first said pair to have the word Go thereon, upward extension of the housing concentrical-

ly positioned to the signal plates and having translucent panels in the sides thereof, a stationary housing centrally positioned in the upper extension having the name or number of the streets cut through the sides thereof and readable through said translucent panels, webbing extending from the vertical corner of the said upward extension and extending outward in vertical alignment with the tangentially positioned signal plates, means to rotate the first said housing to the extent of a quadrant at each interval as controlling means for the traffic at the intersection of highways.

15 In testimony whereof I affix my signature.
LEO M. TORRENCE.
